ATTORNEY

UNITED STATES PATENT OFFICE.

JAMES FRANCIS FERRY, SR., OF FALLS CITY, NEBRASKA.

SAFETY-RAZOR HOLDER.

Original application filed August 11, 1922, Serial No. 581,163. Divided and this application filed January 21, 1924. Serial No. 687,558.

To all whom it may concern:

Be it known that I, JAMES F. FERRY, Sr., a citizen of the United States, residing at Falls City, in the county of Richardson and State of Nebraska, have invented a new and Improved Safety-Razor Holder, of which the following is a specification.

My invention relates to certain new and useful improvements in safety razors of the well known Gillette type and it especially has for its object to provide a blade holder which can be used with the plain blades now commonly employed and which is of such construction and will so cooperate with the blade as to provide a free and clear space between the blade and the guard so that débris can be readily washed out without taking the razor apart.

In the drawings:

Figure 1 is a perspective view of my improved holder, the guard and cap members being separate.

Figure 2 is an elevation and part cross section showing the position of the parts before screwing up on the cap shank.

Figure 3 is a view of the holder and blade ready for use.

Figure 4 is a detailed perspective view of one of the ordinary blades commonly employed with razors of this type.

In the drawing, in which like numerals of reference designate like parts in all of the Figures, 1 represents the handle which carries the usual guard 2, the latter being provided with holes 3 for the cap lugs 9 of the usual cap 8. The guard 2 and handle 1 are bored at 6 to receive the threaded shank 7 of the cap, the parts being clamped together by the tubular nut 4, which screws onto the threaded shank 7 and has a milled finger piece 5 forming an abutment at the end of the handle, whereby the cap and guard can be drawn together to clamp the razor blade 12 between them.

With my invention the guard 2 is provided with teats 11 on the outer face or that face which lies adjacent to the razor blade. The cap 8 may be provided with recesses 10 if desired, although the recesses may be omitted if desired.

My improved holder is adapted for use

with the ordinary razor blade shown in Figure 4 and by reference to Figures 2 and 3 it will be seen that when the parts are clamped together (Figure 3) channels 14 are provided so that washing water may be passed in all directions beneath the blade between it and the guard 2. In this way it is possible to clean the razor thoroughly without loosening the blade or taking the razor apart.

The present application is a division of my application filed August 11, 1922, Serial No. 581,163.

From the foregoing description, taken in connection with the accompanying drawing, the construction and advantages of my invention will be clear to those skilled in the art.

What I claim is:

1. In a razor, a holder including a curved cap and a curved guard and means for positioning and clamping the same together in cooperative relation, said guard having teats on the face opposed to the cap and positioned intermediately of the positioning and clamping means and the edges of the guard whereby when a blade is clamped between the parts the blade will be held in continuous contact throughout with the cap and be spaced from the guard by the teats to leave free cleaning passages between the blade and the guard in all directions for the purposes specified.

2. In a razor, a cap and a guard, means for positioning and clamping the same together in cooperative relation, teats on the guard opposing the face of the cap and positioned at points between the positioning and clamping means and the edges of the guard, and the cap being provided with recesses opposing the teats, and a plain flat razor blade clamped between the cap and guard with that surface which lies adjacent with the cap in contact with the cap throughout to prevent passage of débris between the cap and blade, teats on the guard cooperating with the edges of the cap to hold that surface of the blade opposite the guard out of contact with the guard to leave a space between the said surface and the guard for free passage of débris in all directions.

JAMES FRANCIS FERRY, SR.
